UNITED STATES PATENT OFFICE.

JOHN F. LAHART, OF MINNEAPOLIS, MINNESOTA, AND CHARLES J. BOUR AND FRANK B. HARRIMAN, OF CHICAGO, ILLINOIS.

APPARATUS FOR DRYING AND CONDITIONING GRAIN AND OTHER MATERIALS.

1,232,336.

Specification of Letters Patent.

Patented July 3, 1917.

Application filed November 13, 1913. Serial No. 800,713.

To all whom it may concern:

Be it known that we, JOHN F. LAHART, CHARLES J. BOUR, and FRANK B. HARRIMAN, citizens of the United States, residing at 5 Minneapolis and Chicago, respectively, in the counties of Hennepin and Cook, respectively, and States of Minnesota and Illinois, respectively, have invented certain new and useful Improvements in Apparatus for Drying and Conditioning Grain and other Materials; and we do hereby declare the following to be a full, clear, and exact description of the invention, such as will enable others skilled in the art to which it appertains to make and use the same.

Our invention has for its object to provide an improved drying and tempering apparatus adapted for various different uses, and to such ends generally stated, the invention 20 consists of the novel devices and combinations of devices hereinafter described and defined in the claim.

Before grain can be properly stored, it must be dried to a certain condition, and to 25 properly prepare wheat and other grains for milling, it must be brought to a certain condition in which it contains just the right amount of moisture. This latter treatment is called conditioning and it consists sometimes in drying grain which contains too 30 much moisture, and sometimes in supplying moisture to the grain which is found to be too dry for milling.

Our improved apparatus herein disclosed 35 and claimed, is adapted for drying, or otherwise conditioning grain, and hence, is called a combined drier and conditioner.

Certain other materials require a very 40 analogous treatment; some require simply to be dried; and some require to be moistened.

The apparatus is adapted for such other uses, for example, as the drying of sand, the 45 drying of crushed or granulated ores, or the drying of clay, or of other earth substances containing silica. However, in the further description of this apparatus, it will be considered as if used to dry or condition grain.

In the accompanying drawings which 50 illustrate the invention, like characters indicate like parts throughout the several views.

Referring to the drawings:

Figure 1 is a view in vertical section taken 55 through the improved apparatus, some parts being removed and some parts being shown in full;

Fig. 2 is an enlarged fragmentary section taken on the same line as Fig. 1, or on the line $x^2 x^2$ on Fig. 3;

Fig. 3 is a horizontal section taken on the line $x^3 x^3$ on Fig. 1; and Fig. 4 is a plan view with some parts sectioned, showing the spraying pipe or head for supplying moisture within the apparatus.

It will, of course, be understood that this 65 apparatus may be made in any suitable size. It may be stated, however, that it is especially adapted to be made in very large sizes, having capacity for handling a large amount of grain or other material to be dried. The 70 shell of the bin or hopper is, in the drawings, shown as rectangular in horizontal cross section, but it may be made round, or of any other suitable form.

The numeral 1 indicates the shell of an 75 upright bin having a hopper-like bottom terminating in a suitable air spout 2. This bin may be made of sheet metal, or of any other suitable material, and it may be supported in any suitable way, as for example, 80 by extending the same through the several floors 3 of a building, (see dotted lines in Fig. 1). This bin, as indicated, is shown as rectangular in cross section, and its side plates are shown as reinforced by horizontal 85 beams 4. The bin 1 is provided, just above its hopper bottom, with an interhopper bottom 5, suitably supported therefrom, and provided with a discharge spout 6 that is adapted to be opened and closed, at will, by 90 a gate or slide valve 7, the movements of which, as shown, are controlled by a lever pivoted thereto, and to a bearing 9 on the said spout.

Spaced inward from the walls of the bin 95 1 to afford a surrounding air space 10, is an interlining made up of inwardly inclined horizontally extended slats 11 that afford louver partitions between the air space 10 and the interior of the bin. This louver 11, 100 and the false bottom or interhopper 5 afford a complete inner bin, the vertical walls of which will not permit grain, or similar material to flow outward therethrough, but, nevertheless, provide for the free circulation 105 of air. The slats 11 of this louver may be supported in a great many different ways, but preferably, they are spaced apart by spacing blocks 12, (see Fig. 2) and are bolted, riveted, or otherwise rigidly secured 110 to upright inner bars 13, and upright inner bars 14, the former of which, as shown,

are flat bars, while the latter are angle irons. To space the louver and support the same inward from the walls of the bin 1, lacing bars 15 are preferably secured to the angle bars 14 and to similar angle bars 16 secured on the interior of the walls of the bin, (see Figs. 1 and 2).

Preferably the inner bin formed by the louver 11 is closed at its top by a cover plate 17, while the air surrounding air space 10 is left entirely open at its top. The air spout 2, which connects to the conical lower portion of the air space 10, is shown as connected to a fan or blower 18 of any suitable construction, and the said spout 2 is provided with a vent pipe 19 and is adapted to be closed or opened to any desired extent by a gate valve 21.

The grain or other material to be dried or conditioned is preferably introduced into the central upper portion of the bin through a supply spout 22, the lower end of which extends through the cover 17 and is provided with an adjustable side 23 serving as a gate to vary the size of the delivery end of said supply spout.

This gate 23 is shown as connected to a latch lever 24 that is pivoted to and co-operates with a latch segment 25 secured on the said cover 17.

Extended vertically and axially through the bin is a ladder-like skeleton steam rack made up of upright tubes 26 and horizontal connecting tubes 27. The lower portion of this rack is connected to a steam heating pipe 28 by one or more connecting pipes 29 that extend through the upper portion of the spout 6 at one side of the gate 7. A steam supply pipe 29 is connected to the upper portion of said rack, being, as shown, connected to one of the upright pipes 26 thereof. This so-called steam rack performs two important functions, to-wit, in the first place, it affords a heat radiator for heating the grain or material to be dried, and in the second place, it affords a sort of retarding device preventing too rapid flow of the grain or material at the axis of the bin, and giving chance for the grain to properly flow from the sides of the bin, inward and downward, so that the grain will be thoroughly stirred up and evenly heated.

The heat supplied to the grain or material being dried, will cause a liberation of the moisture primarily contained therein and the vapors will escape through the louver interlining 11 into the surrounding air space 10, and from thence, will be drawn off and carried away by the upwardly moving blast from the blower 18. In fact, this upwardly moving blast from the blower through the air space 10 will assist in drawing the moisture out of the grain.

The flow of the grain or materials in the bin might be regulated by adjustment of the gate or valve 7, and hence, the grain or material may be kept for any desired length of time within the bin, as may be required to effect the proper drying or conditioning. Of course, the supply of grain to the upper portion of the bin should be correspondingly regulated and this may be done by adjustments of the supply gate 23.

The moisture supplying device for use in tempering grain that is too dry for milling, is shown as comprising a water supply pipe 30 which terminates in an endless perforated nozzle or head 31 located immediately over the upper portion of the axially located steam rack. Preferably, the water supply pipe 30 is provided with a globe valve 32 and with a water meter 33, by means of the former of which, the supply of water may be regulated, the said meter serving to indicate the amount of water being supplied to the grain. Obviously, by proper adjustments of the water supply valve 32, and of the supply gate 23 and discharge gate 7, any desired amount of moisture per unit of grain or material may be supplied. Obviously, the water supplied to the grain will be sprayed thereon and delivered evenly around the axis of the bin at the top of the bin and immediately around the point where the grain is delivered into the bin. Otherwise stated, the spout 22 delivers the grain or material through the endless spraying head 31 and the perforations in the latter are arranged to evenly distribute the water inward, toward and around the inflowing stream of grain or material.

The so-called steam rack 26-27 from a broad point of view is a heat radiator, and it will, of course, be understood that either hot water or hot air might possibly, in some instances, be employed as the heat supplying medium.

What we claim is:

The combination with a bin having a discharge orifice in its bottom, of a supply spout for delivering grain or other material into the upper portion of said bin, and a heating pipe having vertical and transverse portions located at the axis of said bin, the outer portion of said bin being free from obstructions and the said pipe affording a retaining device or obstruction at the axis of the bin.

In testimony whereof we affix our signatures in presence of two witnesses.

JOHN F. LAHART.
